UNITED STATES PATENT OFFICE.

WILLIAM GEORGE COLLINS, OF NEW YORK, N. Y.

DESIGN FOR PLUSH FABRIC.

SPECIFICATION forming part of Design No. 25,494, dated May 12, 1896.

Application filed April 11, 1896. Serial No. 587,228. Term of patent 7 years.

To all whom it may concern:

Be it known that I, WILLIAM GEORGE COLLINS, a citizen of the United States, residing at New York, in the county of New York and State of New York, have invented and produced a new and original Design for Plush; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

5 The single figure of the drawing is a representation of my newly-designed plush, and is deemed sufficient to fully illustrate the same.

The leading feature of my design consists in the plush with rococo ornamentation.

o In said drawing, a indicates the body color or field of the plush, on which are ornamental figures b, different in color from the body color. For example, the body of the plush may be maroon or garnet and the figures of pale yellow, or the ground may be white and the figures in black, as in the drawing. The said figures are in irregular scrolls, curved lines, shells, and other irregular lines, together forming an ornamentation in what is commonly known as the "rococo" style. The said scrolls, shells, curved lines, &c., are marginally grouped around open or unornamented spaces a', and between the several marginal groups the ground is diapered, as at a'', or provided with ornamental cross-lines, as at a'''.

What I claim is—

The design for plush, substantially as herein shown and described.

In testimony that I claim the foregoing I have hereunto set my hand this 6th day of March, 1896.

WILLIAM GEORGE COLLINS.
